Inventor
Dona A. HAMILTON

Ch. Farren
Attorney

UNITED STATES PATENT OFFICE.

DON A. HAMILTON, OF SALT LAKE CITY, UTAH.

LADDER.

Application filed November 20, 1922. Serial No. 602,108.

To all whom it may concern:

Be it known that I, DON A. HAMILTON, a citizen of the United States, residing at Salt Lake City, in the county of Salt Lake 5 and State of Utah, have invented certain new and useful Improvements in Ladders, of which the following is a specification.

This invention relates to ladders, and more particularly to a ladder formed of a 10 plurality of jointed sections.

An object of the invention is the provision of a knockdown ladder that can be quickly assembled and disassembled to produce a rigid construction.

15 A further object is the provision of a clamping element for the leg sections that will also retain the rungs in position.

In the accompanying drawings, I have shown one embodiment of the invention. In 20 this showing:

Figure 1 is a front elevation of the ladder assembled,

Figure 2 is a side elevation,

25 Figure 3 is a detail perspective view showing two adjacent leg sections disassembled,

Figure 4 is a transverse sectional view on line 4—4 of Figure 2, and,

Figure 5 is a similar view on line 5—5 of Figure 2.

30 Referring to the drawings, the reference numeral 1 designates generally the leg sections of the ladder, and 2 the rungs. As shown, the leg sections are substantially rectangular in horizontal cross section and the 35 rungs are cylindrical. The end of each leg section is provided with a projecting lug 3. The inner edge of the lug is provided with a portion 4, parallel to the outer edge and is further provided with an inclined or angular portion 5. As shown (see Figure 3) the lugs on the adjacent ends of two leg sections are arranged on opposite sides and are adapted to interlock. A metal band 6 is arranged around the edge of each leg section, forming a space 7 for the reception of the end of the adjacent lug. The inclined faces 5 are provided with substantially semi-circular recesses 8 which aline when the leg sections are assembled, and are adapted to 45 receive a bolt 9, carried by a clamping plate 10 arranged on the inside of the ladder. As shown, this plate is provided with flanges 11, adapted to embrace the front and rear edges of the leg sections. A plate 12 is arranged on the exterior of the leg and this plate is provided with an opening 13 for

the reception of the bolt 9. A wing nut 14 is arranged on the bolt to retain the clamping element in position. Adjacent the ends of the plate 12, it is reduced in thickness as at 15 to allow for the thickness of the metal band 6. Each of the metal bands is provided with openings 16 and the projecting portion of each leg which is received within the space 7 is provided with an opening 17, 60 adapted to aline with the opening 16 of the surrounding band. The ends 15 of the outer clamping plate are provided with pins 18 adapted to be received in these openings. 65

The inner plate 10 is provided with a cylindrical socket 19 for the reception of the rung 2.

70 The operation of the device will be apparent from the foregoing description. When the ladder is to be assembled, the ends 75 of the adjacent leg sections are brought together with the projections 4 received in the spaces 7 formed by the bands 6. The inner clamping plate 10 is then arranged on the inner side of the leg and the bolt 9 passed through the opening 10. The outer clamping plate is then placed in position with the pins 18 arranged in the openings 16 and the nut 14 tightened on the projecting end of the bolt. It will be apparent that the clamping plates together with the pins 18 form a 80 substantially rigid construction which permits the ladder to be subjected to the same use as a rigid ladder having legs formed in one piece. 85

90 It is to be understood that the form of my invention herewith shown and described is to be taken as a preferred example of the same, and that various changes in the shape, size, and arrangement of parts may 95 be resorted to without departing from the spirit of the invention or the scope of the subjoined claims.

Having thus described my invention, I 100 claim:

1. In a ladder, a sectional leg comprising a plurality of sections, a projection formed on each end of each section and adapted to interlock with the end of the adjacent section, and clamping elements, each of said clamping elements comprising a plate arranged on the inside of the leg, a bolt carried by said plate and projecting through the leg sections, a plate carried on the exterior of said leg sections and provided with an opening for the reception of said bolt, and pins carried by said exterior plate, said pins 105 110

being adapted to be received in openings in the adjacent leg sections.

2. In a sectional ladder, a plurality of leg sections, the ends of said sections being provided with projections and recesses, the projection on the end of one leg section being adapted to be received in the recess of the adjacent leg section, a clamping element comprising a plate adapted to be arranged on the inside of said leg sections, said plate being provided with flanges adapted to extend over the edges of said leg sections, a bolt extending from said plate and projecting through said leg sections, an exterior plate having an opening for the reception of said bolt, and means for securing a rung to said first mentioned plate.

3. In a sectional ladder, a plurality of leg sections, the ends of said leg sections being

provided with projections and recesses, the projection on the end of one leg section being adapted to be received in the recess of the adjacent leg section, a plate surrounding the end of each of said leg sections adjacent said recess, and a clamping element comprising a pair of plates, one of which is arranged on each side of the joint of said leg sections, means for securing said plates to each other, and a socket carried by one of said plates, said socket being adapted to receive a rung.

In testimony whereof, I affix my signature in presence of two witnesses.

DON A. HAMILTON.
